UNITED STATES PATENT OFFICE

BRADLEY DEWEY, OF CAMBRIDGE, MASSACHUSETTS, ASSIGNOR TO DEWEY AND ALMY CHEMICAL COMPANY, OF CAMBRIDGE, MASSACHUSETTS, A CORPORATION OF MASSACHUSETTS

COVER-LINING APPARATUS

Application filed February 15, 1928. Serial No. 254,440.

This invention pertains to cover or cap lining apparatus designed to apply an annular band of lining compound to the inner surface of a receptacle cover or cap and relates more particularly to apparatus of that type in which the cover or cap is supported temporarily upon a rotating chuck while receiving the lining compound from a relatively stationary nozzle.

- 10 In machines of the above type the cover supporting chuck rotates and is raised and lowered intermittently, and covers or caps are fed automatically to the chuck and delivered therefrom when the chuck is in its lowered position. The delivery of lining compound from the nozzle is also intermittent, taking place only during periods of elevation of the chuck, but its delivery or non-delivery during such periods is controlled by
- 15 20 a so-called "no-cover, no-compound" mechanism which prevents delivery of compound (even when the chuck is elevated) unless a cover is in compound-receiving position on the chuck. This no-cover, no-compound mechanism usually comprises an actuator, in the nature of a feeler or detector, commonly referred to as a "chuck-pad", to which operative movement is imparted by a cover resting on the chuck, thereby through intermediate 25 30 mechanism, causing the nozzle to open and deliver lining compound to the cover, the pad remaining quiescent and inoperative for such purposes in the absence of a cover from the chuck.
- 35 It has been common, in dealing with substantially flat covers, that is to say, those whose edges are but little, if any, above the center panel, so to determine the normal position of the chuck-pad that the cover, as it is fed forward onto the chuck, engages the
- 40 45 pad with light frictional contact, thus preventing the rapidly advancing cover from overrunning the chuck. Thus, in addition to its main function as a feeler or detector, the pad acts as a stop or retarder for centering the cover on the chuck, and the pad successfully performs this double function so long as the covers are substantially flat. On the other hand, if the edge or rim of the cover or cap is raised to any substantial extent

above its central panel, it becomes impractical to use the pad as a stop element, since if positioned low enough frictionally to engage the center panel of the cover, it tends to dent or bend the upstanding edge or rim of the cover, and for this reason, in accordance with the present invention, I provide a stop member independent of the pad, and movable into and out of the path of the cover at proper intervals by the use of appropriate means hereinafter more fully described.

While the arrangement just outlined (including the independent stop) is efficient and useful in dealing with covers or caps whose edges are but slightly above the center panel, I find that in dealing with covers or caps having very high rims or edges it is impracticable to dispose the chuck-pad at such a normal position or elevation as to permit the high-rimmed cap to pass beneath it without damaging contact. Accordingly, in order that the apparatus may successfully deal with covers or caps of all usual types, regardless of the height of the rims, that is to say, whether such covers or caps are substantially flat or deeply cupped, I have provided (in addition to the independent stop above referred to) means for temporarily elevating the chuck-pad while the cover or cap is advancing onto and leaving the chuck, although I provide for returning the pad to its operative or detecting position immediately before the chuck rises and begins to rotate in performing its usual cycle of operation and thus preserve the usual detector or feeler function of the pad for determining the delivery of lining compound from the nozzle.

Briefly outlined, the sequence of operations of my new apparatus is substantially as follows:

First, with the chuck down and stationary, a cover or cap is advanced toward the chuck, but before the cover reaches the chuck, the chuck-pad is elevated to permit the cover to pass beneath it. As the cover continues to advance, the stop member is moved into its path and brings the cover to rest in centered position upon the chuck. The chuck-pad now descends until it is substantially in contact with the cover on the chuck and the rotating

chuck then rises. The lifting of the chuck with the cover mounted thereon raises the chuck-pad and, through appropriate mechanism, causes the nozzle to open and deliver lining compound to the rotating cover. After a proper interval, the chuck descends, permitting the chuck-pad also to descend, and the nozzle closes. At some time during the above sequence of operations, the stop member has moved out of the path of the cover, and the chuck-pad now rises and the cover is removed from the chuck by suitable and usual means, thus completing the cycle of operations and leaving the parts in position for the reception of another cover.

In the accompanying drawings I have illustrated one desirable embodiment of the invention by way of example, but wish it to be understood that the invention in so far as its broad principle is concerned is not to be restricted to the specific mechanism herein illustrated but is capable of embodiment in equivalent mechanism and without reference to the precise proportions of parts, the relative arrangement of the same, or the exact type of lining machine to which my invention is applied.

In the accompanying drawings,

Fig. 1 is a fragmentary plan view showing certain parts of a cap lining machine of usual type having the present improvements embodied therein;

Fig. 2 is a fragmentary side elevation of the mechanism shown in Fig. 1;

Fig. 2^a is a plan view of a portion of the apparatus shown in Figs. 1 and 2, and showing the mechanism for removing a cover after adhesive has been applied thereto;

Fig. 3 is a fragmentary vertical section, to larger scale, substantially on the line 3—3 of Fig. 1; and

Figs. 4, 5, 6, 7, 8, 9 and 10 are fragmentary, more or less diagrammatic, views, partly in vertical section, illustrating various steps in the cycle of operations of my improved apparatus.

Referring to the drawings, the numeral 1 designates the main frame of the cover lining machine, which in general is of a type well known in the art. The covers or caps may be fed to the lining mechanism by hand, but it is common to feed them automatically, and I have here shown the lower end of a chute 2 adapted to deliver the covers or caps in orderly succession onto the table-like top 1^a of the main frame or to a guideway carried thereby. This chute is provided with an escapement 3 at its lower end which permits one cover or cap at a time to slide from the lower end of the chute and into engagement with a reciprocating feed member 4 which is actuated in properly timed relation by driving mechanism of usual character, not shown, and which advances the cover along

the table top 1^a, or the guideway, into compound-receiving position.

At its right-hand side, as viewed in Figs. 1 and 2, the machine frame has an upright member 5 supporting a table 5^a which carries the essential elements of the no-cover, no-compound mechanism hereinafter more fully described. The table 5^a also supports a pair of brackets 6 providing bearings for a shaft 7 having a sprocket wheel 8 at one end which receives a sprocket chain passing downwardly and about a sprocket wheel 9 on the main drive shaft 10, the latter being mounted in suitable bearings carried by the main frame 1. The shaft 10 is also provided with a sprocket wheel 11 driving a chain 12 which engages a sprocket wheel 13 on a shaft 14 journaled in the main frame. The shaft 14 actuates mechanism of usual character, not shown, for operating the escapement, the cover-feeding device, the chuck, and the cover delivery means.

The main frame 1 is provided with suitable guides for a vertically reciprocating and rotating chuck 15 of usual type, which is raised and lowered intermittently while continuously rotated by the mechanism just referred to. The upper surface of this chuck is normally substantially flush with the upper surface of the table 1^a or guideway along which the covers or caps are advanced by the feed device 4, and this chuck is provided with an axial cavity or recess 16 in its upper surface adapted at times to receive the chuck-pad, hereinafter more fully described, and which constitutes the actuating means for determining delivery of lining compound to a cover resting upon the upper surface of the chuck.

An adjustably supported nozzle 17, having a delivery nose 18, is disposed above the chuck 15 and eccentric with respect to the axis thereof, and in such position that compound delivered from the nose 18 of the nozzle is deposited at the desired radial distance from the center of a cover resting on and coaxial with the chuck. The nozzle 17 is provided with a controlling valve, not shown, having an actuating element 21^a, and is supplied with lining compound by means of a flexible conduit 19 leading from a suitable reservoir 20. This reservoir may be arranged at any desired point and the compound may be caused to flow therefrom either by gravity or pressure, as may be preferred. The valve in the nozzle 17 is normally closed but may be opened by upward movement of a flexible wire connection 21 secured at its lower end to the valve-actuating element and at its upper end to a sleeve member 22 adjustably secured to the lower end of a vertically sliding rod 23. The rod 23 slides in a bore in a boss 24 projecting upwardly from a base member 5^b mounted on the table 5^a. The rod 23 is preferably provided with a stop collar 25 normally bearing against the upper sur-

face of the boss 24 and is furnished near its upper end with spaced fixed collars 26 between which is positioned the forked end 27 of a lever 28. This lever is fulcrumed upon a pin 29 mounted in spaced ears 30 at the upper end of a vertical rod 31 sliding in a guideway in a boss 32 projecting up from the base member 5^b. The lever 28 has also an arm 33 which extends to a point below the shaft 7 and which is provided with a cam follower roll which engages a cam 34 on the shaft 7. A pin 35 engages the under surface of the arm 33 of this lever, such pin sliding in a bore in a boss 36 carried by a bracket 37 projecting from the base member 5^b. The pin 35 rests upon a coil spring 35^a which urges the pin upwardly and thus keeps the cam follower roll of the arm 33 constantly in engagement with the cam 34. Under normal conditions the lever 28 fulcrums about its end 27, and as the cam 34 rotates and depresses the rear end of the lever, the rod 31 moves freely downward in its guideway and thus the downward movement of the arm 33 of the lever fails to lift the rod 23 and to open the valve in the nozzle 17.

The boss 32 is provided with bearings for a transverse shaft 40 carrying a dog 41 which, under certain conditions, is swung beneath an abutment 42 carried by the rod 31. When the dog 41 is placed beneath the abutment 42, the dog constitutes a stop preventing downward movement of the rod 31; and then, when the lever arm 33 is moved downwardly by the cam 34, the lever 28 fulcrums about the pin 29, thus raising the forked end 27 of the lever and lifting the rod 23, thereby opening the valve in the nozzle and permitting delivery of lining compound.

On the shaft 40 there is pivoted for limited downward movement a weighted member 43, and a spring 44 is interposed between the members 43 and 41 so that upward movement of the member 43 resiliently urges member 41 in a clockwise direction, as viewed in Fig. 2, so as to place it beneath the abutment 42. On the other hand, the weighted member 43 normally tends to swing the member 41 in the opposite direction. The member 43 rests upon an upwardly bent arm 45 of a pin 46 projecting horizontally from one end of a lever 47 fulcrumed at 48 upon a suitably fixed part carried by the base member 5^a. A fixed stop 45^a may be provided for supporting the weight of the parts 43, 45 and 46 in their normal position, as shown in Fig. 2. The lever 47 has a second arm 49 hereinafter further referred to.

The base member 5^b is furnished with a hollow upstanding boss or housing 50 having a vertical slot 51 in one side and provided with a cover 52 having an axial guide opening for the upper part 53 of the two-part stem of an actuator in the nature of a feeler or detector, and which hereinafter, in accordance

with the usual nomenclature of the art, will be referred to as a "chuck-pad". The lower member 54 of this two-part stem is guided to slide vertically in a bushing 55 in the base member 5^b and carries the chuck-pad 56 at its 70 lower end.

The upper stem part 53 is provided at its lower end with the top element 57 of a cage having the lower part 58 and which is disposed within the cavity in the boss or housing 50 and which has an axial guide opening in its bottom for the reception of the upper end of the lower stem part 54. The stem part 54 is provided with a fixed collar (preferably the inner race of a ball bearing 59) at a point 75 within the cage 58, such collar or ball bearing constituting a stop to limit downward movement of the stem part 54 with respect to the cage 58, although permitting the stem part 54 to rotate freely and to move upwardly 80 relative to the cage. A light compression spring 60 within the cage 58 normally holds the stem part 54 in its lowermost position.

The cage 58 is provided with a bracket arm 61 projecting out through the slot 51 in the 90 housing or boss 50, and this bracket arm carries a pin 62 forming a fulcrum for a lever 63 having an arm which is disposed transversely across and immediately above the arm 49 of the lever 47 above described. The lever 95 63 is provided with a second arm 64 which is normally held by a tension spring 64^a in contact with an abutment element 65 secured to the upper end of the lower stem member 54. When the parts are in their normal position, the lever 63 is substantially horizontal and exerts little or no pressure against the lever arm 49.

The upper end of the upper stem member 53 is provided with a flanged sleeve 66, 105 preferably normally spaced from the top of the housing or boss 50, as indicated at 67 and the forked end 68 of a lever 69 is disposed between the upper and lower flanges of the sleeve 66. The lever 69 is fulcrumed upon a shaft 70 mounted in brackets 71 projecting up from the base 5^b, and this lever is furnished with a rearwardly extending arm 72 provided with a cam follower roll 73 engaging a cam 74 on the shaft 70. A strong spring 110 69^a engaging the arm 69 holds the cam follower roll 73 constantly in contact with the cam 74.

The frame is provided with bearing bosses 75 and 76 providing guideways for a vertically sliding rod 77 having a bracket 78 at its lower end. This bracket carries a stop member 79 which is normally disposed above the plane of movement of the covers or caps but which may be lowered into the path of the advancing cover or cap. The stop 79 is preferably adjustable with respect to the bracket 78 as by means of a bolt 78^a passing through an elongate slot in the stop and engaging a screw-threaded opening in the bracket so that 120 125 129

it may be adapted for use with covers or caps of different diameters, and it is normally so adjusted that when an advancing cap or cover arrives at compound-receiving position 5 where it is coaxial with the chuck 15, it will engage the stop and thus be positively stopped. A spring 80 tends to lift the rod 77 and normally holds the stop member in inoperative position. The upper end of the 10 rod 77 is provided with an arm 81 carrying a cam follower roll engaging a cam 82 on the shaft 7.

The main frame 1 is provided with a pair of sliding rods 83 having cover-engaging 15 fingers 84 at their ends adapted at the proper time in the cycle of operations to engage a cover resting upon the chuck 15 and to remove the cover from the chuck.

The operation of the above mechanism is 20 substantially as follows, having reference particularly to Figs. 4 to 9 inclusive as indicating the cycle of operations:

Referring to Fig. 4, the chuck 15 is in its lowermost position with its top substantially 25 flush with the upper surface of the table 1^a or guideway along which the covers are moved; the chuck-pad or actuator 56 is in its lowermost position, spaced just above the upper surface of the table or guideway; the valve in 30 the nozzle 17 is closed; and the stop member 79 is in its upper or normal position. Assuming now that a cap or cover has been delivered from the chute 2 by the operation of the escapement 3, such cap or cover is engaged by 35 the feed device 4 and advanced toward the chuck 15. As the cover nears the chuck, the cam 74 actuates the lever 69, thereby lifting the upper stem member 53 with the cage 58 and the lower stem member 54, thus elevating 40 the chuck-pad or actuator 56 until it occupies the position shown in Fig. 5, where it is sufficiently above the upper surface of the chuck to permit a cap or cover C to pass freely beneath it, even though such cap or cover have 45 a deep edge or rim. At substantially the same time, the cam 82 depresses the rod 77, thus placing the stop 79 in the path of the advancing cover. As above stated, the stop is so adjusted that when the cover engages it, the 50 cover is substantially coaxial with the chuck 15. After the cover has thus been placed over the chuck and brought to rest, the continued rotation of the shaft 7 and the cam 74 permits the lever 69 to return to its normal position, thus permitting the chuck-pad 56 to 55 drop back to its normal position, as shown in Fig. 6. In this position it may be in contact with the central panel of the cover or spaced slightly above the latter as may be preferred.

60 The chuck 15 is now elevated in the usual manner to the position indicated in Fig. 7, and as the chuck rises, the cover presses upwardly against the chuck-pad 56, thus lifting the stem part 54. Since the lever 69 is at this 65 time held in its lowermost position by the

heavy spring 69^a, the upper member 53 of the stem does not partake of the upward movement of the lower part 54, and the collar 59 on the lower part moves upwardly in the cage 58 compressing the spring 60. This relative upward movement of the stem 54 with respect to the cage 58 causes the abutment member 65 to elevate the lever arm 64, thus depressing the lever arm 63 and pushing down the arm 49 of the lever 47. The pin 46 is thus elevated and its bent end 45 lifts the weighted member 43 and swings the dog 41 beneath the abutment 42. Immediately thereafter the rotation of the cam shaft 7 brings the active portion of the cam 34 into engagement with the follower roll on the lever arm 33, thus lifting the arm 28, elevating the rod 23, and through the connection 21 opening the valve in the nozzle 17. The lining compound is now delivered from the nozzle as the rotation of the chuck 15 rapidly turns the cover, and an annular band of lining compound is laid upon the inner surface of the cover at the desired radial distance from the center of the latter, such distance being determined by proper initial adjustment of the nozzle 17.

After the cover has made a predetermined number of rotations, the chuck 15 descends, and during this downward movement the spring 60 pushes the stem member 54 and the pad 56 down so that the pad remains substantially in contact with the cover. During this downward movement of the stem member 54, the lever 63 is restored to its normal position by the spring 64^a, permitting the lever 47 to resume its normal position, and when the cam 34 releases lever arm 33, the weighted member 43 drops back to substantially horizontal position, swinging the dog 41 out from beneath the abutment 43 and thus permitting the rod 23 to descend and close the valve in the nozzle 17.

At some time during the above sequence of operations the cam 82 has permitted the spring 80 to restore the stop member 79 to its normal inoperative position so that it will not interfere with the proper removal of the lined cover or cap from the chuck.

The chuck, cover, and pad now occupy substantially the position indicated in Fig. 8, and in order that the cover may be removed from beneath the pad, the pad is again lifted to the position shown in Fig. 9 by the action of the cam 74. While the pad is in the position indicated in Fig. 9, the rods 83 advance and their fingers 84 engage the lined cover and remove it from the chuck, whereupon the pad 56 again descends and the parts assume the position indicated in Fig. 4.

The above normal cycle of operations occurs providing that a cover or cap is fed forwardly in the proper way at the beginning of each cycle, but in the event that a cover fails for any reason to feed forward onto the chuck before the latter rises, the parts assume the po-

sition indicated in Fig. 10. In this case the upward movement of the chuck does not raise the pad 56, the latter being received in the cavity 16 in the chuck, and thus there is no relative movement of the stem parts 53 and 54 and no such actuation of the lever 63 as is necessary to initiate delivery of lining compound from the nozzle. Thus, whenever the mechanism fails to deliver a cover to the chuck, no lining compound is delivered from the nozzle even though the actuating cams continue to rotate, it being noted that rotation of the cam 34 has no effect upon the valve actuating rod 23 unless the dog 41 has first been placed beneath the abutment 42.

While I am aware that various elements of the above mechanism are old and well known, particularly those parts which have been referred to as the no-cover, no-compound mechanism, I have believed it necessary to describe many of these parts in detail in order more clearly to indicate the novel function and purpose of my present improvements. Furthermore, while I have shown these improvements as applied to a specific type of no-cover, no-compound mechanism, I believe that it is possible that the principle of the invention may be applicable to no-cover, no-compound mechanisms of other types, and I do not wish to limit myself to its application, in so far as its broad principle is concerned, to the particular mechanism herein disclosed.

I further contemplate that various changes in design, proportion of parts, and relative arrangement of the parts herein disclosed, and the substitution of all known or useful equivalents may be made without departing from the spirit of the invention.

I claim:

1. Apparatus of the class described having a no-cover, no-compound mechanism including a vertically movable chuck-pad which moves in response to upward pressure of a cover thereagainst and thereby initiates delivery of lining compound, said apparatus comprising means for lifting said pad above its normal position to permit a deep-rimmed cover to advance horizontally beneath it.

2. A cover lining apparatus of the kind having a no-cover, no-compound mechanism including an actuator which moves from a normal inoperative position in response to the pressure of a cover thereagainst, said apparatus comprising means for moving the actuator out of the path of the cover as the latter advances toward compound-receiving position.

3. Apparatus of the class described having a no-cover, no-compound mechanism including a chuck-pad whose normal function in response to pressure of a cover thereagainst is to initiate delivery of lining compound, said apparatus comprising means for moving said pad, without thereby initiating delivery of

compound, to admit a cover beneath the pad.

4. A cover lining apparatus of the class described having means, including an actuator, for delivering lining compound, said actuator moving in response to upward movement of a cover and thereby initiating delivery of compound to the cover, and additional means for moving the actuator in the same direction without initiating delivery of lining compound.

5. Apparatus of the class described having means for delivering lining compound and an actuator movable by pressure of a cover thereagainst to initiate delivery of lining compound to the cover, and means for advancing the cover in a predetermined path to a compound-receiving position and for removing a lined cover from said position, said apparatus comprising means for moving the actuator out of the path of the cover without operating the compound delivery means as the cover advances to compound-receiving position.

6. Apparatus of the class described having a no-cover, no-compound mechanism including a movable chuck-pad whose normal function in response to pressure exerted by a moving cover is to initiate delivery of lining compound, said apparatus comprising means for moving said pad, without thereby initiating delivery of compound, both before and after its normal functioning, whereby to permit a cover to be placed beneath the pad and to be removed from beneath the pad, respectively.

7. Apparatus of the class described having means for delivery lining compound and an actuator engageable with a cover and by pressure of the cover thereagainst moving from a normal inoperative position to initiate delivery of living compound to the cover, and means for advancing the cover in a predetermined path to a compound-receiving position and for removing a lined cover from said position, said apparatus comprising means for moving the actuator out of the path of the cover without operating the compound delivery means, as the cover is removed from compound-receiving position.

8. Apparatus of the class described having a no-cover, no-compound mechanism including a movable chuck-pad whose normal function in response to pressure exerted by a moving carrier is to initiate delivery of lining compound, said apparatus comprising means for moving said pad, without thereby initiating delivery of compound, to admit a cover beneath the pad and to permit the pad to return to its original position ready to perform its normal function, and means operative, after the pad has functioned to initiate and terminate delivery of lining compound, for again lifting the pad without initiating delivery of compound whereby to permit the cover to be removed from below the pad.

9. Apparatus of the class described having means for delivering lining compound and an actuator engageable with a cover and by movement in response to pressure of the cover thereagainst initiating delivery of lining compound to the cover, means for advancing the cover in a predetermined path to a compound-receiving position and for moving a lined cover from said position, said 10 apparatus comprising means for moving the actuator out of the path of the cover, without operating the compound delivery means, as the cover advances to compound-receiving position and again as the lined cover is moved from said position.

10. A cover lining apparatus of the kind having a vertically movable rotary chuck for supporting a cover while being lined, means for advancing a cover horizontally onto the 20 chuck while the latter is stationary and in its lowest position, and a no-cover, no-compound mechanism for delivering lining compound to a cover on the chuck, said mechanism including a movable chuck-pad adapted 25 to initiate delivery of compound by pressure thereagainst of a cover resting on the chuck as the latter moves upwardly, said apparatus comprising means for shifting the chuck-pad from normal position to permit a deep 30 rimmed cover to advance beneath it and for permitting the chuck-pad to resume its normal position as the cover comes to rest on the chuck.

11. Apparatus of the class described having a vertically movable chuck-pad, a reservoir for lining compound, a valve for determining delivery of compound from the reservoir, and valve opening means which becomes operative when the chuck-pad moves upward- 40 ly in response to pressure of a cover thereagainst, said apparatus comprising means for lifting the chuck-pad, the valve operating means being unresponsive to elevation of the chuck-pad by said lifting means.

12. A cover lining apparatus of the kind having a vertically movable rotary chuck for supporting a cover while being lined, means for advancing a cover horizontally onto the chuck and for removing a cover from the 50 chuck while the latter is stationary and in its lowest position, and a no-cover, no-compound mechanism for delivering lining compound to a cover on the rotating chuck, said mechanism including a vertically movable 55 chuck-pad above the chuck, said pad being adapted to initiate delivery of compound by pressure thereagainst of a cover resting on the chuck as the latter moves upwardly, said apparatus comprising means for lifting the 60 chuck-pad to permit a deep-rimmed cover to advance onto the chuck without engaging the chuck-pad.

13. A cover lining apparatus of the kind having a nozzle for delivering lining compound to a cover and an actuator for deter-

mining delivery of compound from the nozzle, said actuator being movable along a pre-determined path and moving in response to pressure of a cover thereagainst, thereby initiating delivery of compound, and means for advancing a cover along a path substantially perpendicular to and intersecting the path of the actuator, said apparatus comprising means for moving the actuator away from the path of the cover as the cover approaches the intersection of said paths.

14. A cover lining apparatus of the kind having a nozzle for delivering lining compound to a cover and an actuator for determining delivery of compound from the nozzle, said actuator being vertically movable and moving in response to upward pressure of a cover thereagainst to initiate delivery of compound, and means for advancing a cover in a substantially horizontal path intersecting the path of the actuator, said apparatus comprising means for lifting the actuator above the rim of the advancing cover to permit said rim to pass beneath it and for dropping the actuator as the central part of the cover reaches the intersection of said paths.

15. Apparatus of the class described having a rotary vertically movable chuck, cover advancing means, a stop device, compound delivery means, a vertically movable chuck-pad disposed above and normally adjacent to the chuck, said apparatus comprising means for lifting the chuck-pad from the chuck, means for advancing a cover onto the chuck, means for placing the stop in position to check the cover when the cover is centered on the chuck, means for dropping the chuck-pad to normal position, means for raising the chuck with the cover and thereby lifting the chuck-pad, means for initiating the delivery of lining compound in response to this upward movement of the chuck-pad, means for rotating the chuck, means for stopping rotation of the chuck and allowing it to descend with the cover and chuck-pad, means for stopping delivery of compound in response to descent of the chuck-pad, means for removing the stop from the vicinity of the cover, means for lifting the chuck-pad, means for removing the cover from beneath the chuck-pad, and means for allowing the chuck-pad to return to normal position.

16. Apparatus of the class described having a no-cover, no-compound mechanism including a movable chuck-pad, said chuck-pad having a supporting stem comprising relatively movable parts, means for moving all of the parts of the stem as a unit whereby to remove the pad from normal position, one of said parts moving relatively to the other when the pad is subjected to pressure, thereby initiating delivery of lining compound.

17. Apparatus of the class described having a no-cover, no-compound mechanism in-

cluding a vertically movable chuck-pad provided with a guiding stem comprising aligned relatively movable upper and lower parts, means limiting separation of said stem parts, 5 means engaging the upper stem part for lifting both parts as a unit, thereby lifting the pad, and means actuatable by upward movement of the lower stem part relatively to the upper stem part for initiating delivery of lining compound.

18. Apparatus of the class described having means for delivering lining compound, said apparatus comprising a vertically movable stem having relatively movable upper and lower parts, a chuck-pad attached to the lower end of the lower stem part, a sleeve-like member carried by the upper stem part, said sleeve-like member embracing the upper end of the lower stem part, a stop element on the 15 lower stem part disposed within the sleeve-like member to limit separation of the stem parts, a lever fulcrumed on the sleeve-like member and having an arm engaging the lower stem part, said lever rocking when the 20 lower stem part moves relatively to the upper stem part and thereby initiating delivery of lining compound, and means engaging the upper stem part for lifting both stem parts as a unit, the lever remaining inoperative during 25 such lifting movement.

19. Apparatus of the class described having means for delivering lining compound, said apparatus comprising a vertically movable stem having relatively movable upper and lower parts, a chuck-pad attached to the lower end of the lower stem part, a cage carried by the upper stem part, said cage receiving the upper end of the lower stem part, said upper end of the lower stem part having an 35 enlargement disposed within the cage to limit separation of said parts, a compression spring within the cage tending to separate the stem parts, a lever mounted upon the cage, a spring tending to hold one arm of the lever in contact with an abutment carried by the lower stem part, the lever having a second arm normally disposed in such operative relation to compound delivery means that tipping of the lever by upward movement of the lower stem 45 part relative to the cage results in delivery of lining compound, and means engaging the upper stem part for lifting the latter with its cage and the lower stem part as a unit, the lever remaining inoperative during such lifting movement.

20. A cover lining apparatus of that kind having means for supplying lining compound to the cover, said means including an element which responds to the pressure of a cover 50 thereagainst and by such response initiates delivery of the compound, means for advancing a cover toward compound-receiving position, a stop normally disposed out of the path of the advancing cover, and means for moving the stop into position to check the cover

when the latter arrives at compound-receiving position.

21. A cover lining apparatus of that kind having means for supplying lining compound to the cover, said means including an element 50 which responds to the pressure of a cover thereagainst and by such response initiates delivery of the compound, means for advancing a cover toward compound-receiving position, a stop normally disposed out of the path 55 of the advancing cover, and cam controlled means for moving the stop into position to check the advance of the cover and for thereafter removing the stop from the path of the cover.

22. A cover lining apparatus of the kind having a nozzle for delivering lining compound to a cover and an actuator for determining delivery of compound from the nozzle, the actuator operating in response to pressure of a cover thereagainst, means for advancing a cover into compound-receiving position, and a movable stop for checking advance of the cover, said apparatus comprising means for moving the actuator out of the path of the advancing cover and for placing the stop in the path of the cover.

23. A cover lining apparatus of the kind having a no-cover, no-compound mechanism including an actuator which responds to the pressure of a cover and thereby initiates delivery of compound, means for advancing a cover toward compound-receiving position and for removing a lined cover from compound-receiving position, said apparatus comprising a stop, means for temporarily disposing the stop in the path of the advancing cover, and means for temporarily removing the actuator from the path of the advancing cover.

24. Apparatus of the class described having means for delivering lining compound and a vertically movable actuator engageable with the central part of a cover and by movement in response to upward pressure 110 of the cover thereagainst initiating delivery of lining compound to the cover, and means for advancing a cover in a substantially horizontal path to a compound-receiving position beneath the actuator and for removing a lined cover from said position, said apparatus comprising means for lifting the actuator out of the path of the cover, without operating the compound delivering means, as the cover advances to a position beneath the actuator, and means for stopping the cover in compound-receiving position.

25. A cover lining apparatus of the kind having a nozzle for delivering lining compound to a cover and an actuator for determining delivery of compound from the nozzle, said actuator being vertically movable and moving in response to upward pressure of a cover thereagainst to initiate delivery of lining compound, and means for advancing a 125

cover in a substantially horizontal path intersecting the path of the actuator, said apparatus comprising stop means for stopping the cover when its center is substantially at the intersection of said paths, and means for lifting the actuator to such a height, as the cover approaches the intersection of said paths that it clears the rim of the advancing cover and for thereafter dropping the actuator into substantial contact with the cover while the latter engages the stop means.

26. A cover lining apparatus of the kind having a no-cover, no-compound mechanism including an actuator which responds to the pressure of a cover and thereby initiates delivery of compound, means for advancing a cover toward compound-receiving position, and means for removing a lined cover from compound-receiving position, said apparatus comprising a movable stop normally disposed to one side of the path of the cover, and means for temporarily disposing said stop in the path of the cover and for restoring the stop to normal position before the cover removing means operates.

27. A cover lining apparatus of the kind having a vertically movable rotary chuck for supporting a cover while being lined, means for advancing a cover horizontally onto the chuck and for removing a cover from the chuck while the latter is stationary and in its lowest position, and a non-cover, no-compound mechanism for delivering lining compound to a cover on the chuck, said mechanism including a vertically movable chuck-pad above the chuck, said pad being adapted to initiate delivery of compound by pressure thereagainst of a cover resting on the chuck as the latter moves upwardly, said apparatus comprising means for lifting the chuck-pad from normal position as a cover advances onto the chuck, for stopping the cover when the latter is centered on the chuck, and for permitting the chuck-pad to return toward its normal low position before the chuck reaches its uppermost position.

28. Apparatus of the class described having means for delivering lining compound and a vertically movable actuator engageable with the central part of a cover and by movement in response to upward pressure of the cover thereagainst initiating delivery of lining compound to the cover, and means for advancing a cover in a substantially horizontal path to a compound-receiving position beneath the actuator and for removing a lined cover from said position, said apparatus comprising means for lifting the actuator out of the path of the cover without operating the compound-delivering means, as the cover advances to a position beneath the actuator, and means for stopping the cover in compound-receiving position, and means for again raising the actuator, without operating the com-

pound delivery means, as the lined cover is moved from compound-receiving position.

29. A cover lining apparatus of the kind having a vertically movable rotary chuck for supporting a cover while being lined, means for advancing a cover horizontally onto the chuck and for removing a cover from the chuck while the latter is stationary and in its lowest position, and a no-cover, no-compound mechanism for delivering lining compound to a cover on the rotating chuck, said mechanism including a vertically movable chuck-pad above the chuck, said pad being adapted to initiate delivery of compound by pressure thereagainst of a cover resting on the chuck as the latter moves upwardly, said apparatus comprising means for lifting the chuck-pad as the cover advances onto the chuck and for dropping the pad when the cover is centered on the chuck, a movable stop device, and means for placing the stop device in the path of advance of the cover to bring the latter to rest in centered relation to the chuck.

30. A cover lining apparatus of the class described having a no-cover, no-compound mechanism, an adjustable delivery nozzle, a controlling element for a valve within the nozzle, a compound supply reservoir, a flexible conduit leading from the reservoir to the nozzle, and a flexible connecting element for transmitting movement from the no-cover, no-compound mechanism to the valve controlling element in the nozzle.

31. A cover lining apparatus of the kind having a no-cover, no-compound mechanism including a compound delivery nozzle and a detector for determining delivery of compound from the nozzle, said apparatus comprising means for advancing a deep-rimmed cover to an operative position relative to the nozzle, the detector being normally disposed in the path of the advancing cover, and means for displacing the detector from normal position, during advance of the cover so as to permit substantially unimpeded advance of the cover.

Signed by me at Cambridge, Massachusetts, this 9th day of February, 1928.

BRADLEY DEWEY.
